UNITED STATES PATENT OFFICE.

GEORGE H. FORD, OF NEW HAVEN, CONNECTICUT, ASSIGNOR TO THE
GRILLEY COMPANY, OF SAME PLACE.

DESIGN FOR A COFFIN-PLATE.

SPECIFICATION forming part of Design No. 22,724, dated August 22, 1893.

Application filed July 24, 1893. Serial No. 481,352. Term of patent 7 years.

To all whom it may concern:

Be it known that I, GEORGE H. FORD, of New Haven, in the county of New Haven and State of Connecticut, have invented a new Design for a Coffin-Plate; and I do hereby declare the following, when taken in connection with accompanying drawing and the letters of reference marked thereon, to be a full, clear, and exact description of the same, and which said drawing constitutes part of this specification, and represents a face view of a coffin-plate illustrating my design.

This invention relates to a design for a coffin or other plate, and the design consists in the configuration and ornamentation as hereinafter described and shown in the accompanying illustration.

I have illustrated the design herein, as applied to a coffin-plate, but it will be understood that it is equally applicable to the socket-plates of a coffin-handle. The plate,

which is oval in form, comprises a body A, having a plain surface, and a border composed of simple reversely curved scrolls B and C, having curved ends, which are abutted against each other, the adjacent ends of the scrolls B being turned outward, and forming slight projections beyond the general outline of the plate. Beads D D, interposed between the projecting ends of the scrolls B, at the ends of the plate, give additional finish to the design.

I claim—

The design for a coffin or other plate, as herein shown and described.

In testimony whereof I have signed this specification in the presence of two subscribing witnesses.

GEORGE H. FORD.
